DISPENSING CONTAINER

Reed Elliott Jacobs, Hayward, Calif., assignor of forty per cent to Marie M. Bolton, Oakland, Calif.

Application May 2, 1934, Serial No. 723,530

5 Claims. (Cl. 221—11)

This invention is a dispensing container, forming a packing receptacle for various commodities in liquid, powder, granular or flake form, such as milk, syrups, salt, sugar, powdered soaps and other pourable products, and is designed to overcome the defects and high cost of dispensing devices now in use, and which consist of individual spouts or closures which are separately formed from the container and attached thereto. The 10 pouring spouts or lips now in use are usually formed of metal, and in some cases of cardboard, and are not formed from a portion of the container or the cover therefor.

These spouts usually leak about their mounting slots, and when they are made of metal, add considerably to the cost of manufacture of the containers when considered in the light of the enormous volume of such containers produced.

This invention contemplates the forming of 20 the spout or dispensing aperture from a portion of the container and is maintained integral therewith, and the material of the container with the spout or closure portion forms its own hinge, while a sealing disc or diaphragm which is merely pasted over the closure or spout portion to seal the same for shipment, reinforces, and makes responsive, the hinge portion, and forms auxiliary sealing means when the seal has been broken by contact of the edges of rupture.

30 This diaphragm is preferably formed of a thin paraffine paper resilient in nature or an elastic or resilient material, such as rubber, rubberized paper or fabric, or tough paper such as the usual "kraft" papers which are extensively used as wrapping paper and in the manufacture of bags, since this paper is tough, resistant to bending and resilient, and which in connection with the cardboard from which cartons are usually made (and which has little inherent resiliency) 40 normally maintains the closure in closed position.

Agar-agar forms a very suitable paste for the diaphragms for fluid containers since it is non-contaminating, and agar-agar or paraffine is very 45 desirable for use as pasting means for cartons when paper is used for the diaphragm, or rubber cement may be used provided a non-contaminating solvent for the rubber is employed.

The main object of the invention is to provide 50 a pouring spout for containers which spout is an integral part of the container and made operable at will, and to provide means for hermetically sealing the spout portion for shipment.

Another object of the invention is to provide 55 a container cover with a portion normally held in

closing position within an opening, the interposed material from the opening forming the portion, the portion in connection with a portion of the cover forming a hinge.

A further object of the invention is to provide 5 means for releasing the closure at will and also for normally retaining the closure within the opening. A still further object of the invention is to seal the closure portion during shipment with contents by means of a resilient diaphragm 10 in conjunction with a non-contaminating adhesive for application of the diaphragm.

Other objects and advantages of the invention will become apparent as the following description is read on the drawing forming a part of this 15 specification and in which similar reference characters are used to designate similar parts throughout the several views, of which:

Fig. 1 is a fragmentary perspective view of a 20 container with the invention applied thereto.

Fig. 2 is a modification of the invention in which the rim of the cover does not form a part 25 of the closure, and shows side releasing means for the closure.

Fig. 3 is a modification of Fig. 2 showing end 30 releasing means.

Fig. 4 is a section taken on line 4—4 of Fig. 2.

Fig. 5 is a modification of Fig. 2 showing a 35 central releasing slot.

Fig. 6 is a modification of Fig. 1 showing only 40 a portion of the cover rim and also a portion of the top of the container forming an integral reinforcing portion of the closure.

Fig. 7 is a modification of Fig. 1 applied to a 45 rectangular container.

Fig. 8 is a modification of Fig. 2 and Fig. 5 50 for application to liquid containers.

Fig. 9 is another modification of the invention.

Fig. 10 is a section taken on line 10—10 of 55 Fig. 9.

The invention consists of a container body 12 having a cover 13 which is provided with a rim 14, which rim is either pasted or otherwise sealed to the body 12, the cover 13 having a closure 45 formed from a portion thereof, the removal of this portion forming a pouring aperture or spout.

As shown in Fig. 1, the closure 15 is formed by slitting or weakening the cover along two radially converging lines 16 and 17, and about the rim, the portion 18 between the terminals of the slits or lines being left integral with the cover proper and forming a hinge for the closure. These slits, at the time of manufacture, may extend only part way through the thickness of 50 the material, in which case no diaphragm is re-

quired. When slit through, a diaphragm 19 of rubber, tough paper or similar material, is pasted over the closure, using a non-contaminating adhesive.

5 It will be noted that by the combination of an underbody 13 of non-resistant pressboard and a superposed flexure resistant, resilient reinforcement 19, the closure 15 will be normally retained in a closed position and the hinge portion 10 18 will be effective throughout the entire time in which such products are usually dispensed, while the cardboard of the cover might readily break off in the interim.

The lip 20 fits within the slot formed in the 15 rim of the cover, fully closing the dispensing opening and providing convenient means for raising the closure.

In Fig. 2, a modification is shown in which the closure 21 does not continue into the rim 14 20 but terminates at its outer edge 22 substantially parallel with the inner surface of the container cover, so that when closed, the end will rest on the top edge of the container body. An implement receiving slot may be provided in the 25 cover member as shown at 23, or in the closure portion as shown at 24, the assembly being sealed by the diaphragm 25 by means of adhesive 26.

In Fig. 3, another modification is shown in which the radially converging slits 27 and 28 30 terminate in a slot 29, while in Fig. 5, the slot 30 is formed centrally of the closure 31.

In Fig. 6, another modification is shown in which the structure is similar to that shown in Fig. 1 except that the lip includes only a portion 32 of the rim and additionally includes a 35 portion 33 of the upper end of the container body 12, forming a through slot 34 when this portion is slit out. This forms a reinforced lip which is convenient to open, the portions 32 and 33 being pasted together and thereby forming a rigid member.

The modification shown in Fig. 7 is identical in all respects to that shown in Fig. 1 except as applied to a rectangular container, the closure 45 45 having the angular lip 36 which fits over the corner 37 of the body 38, and being formed from the rectangular cover 39.

Another modification is shown in Figs. 9 and 10 in which the cover is slit or weakened along 50 the lines 40 and 42, which are connected by a slit 41 intermediate their length, and which form the closure members 43 and 44 as is clearly shown in Fig. 10.

In Fig. 8 is a modification which is especially 55 applicable for use with metal containers such as milk and syrup cans which require both, a pouring aperture and a vent. In this modification, the metal is weakened as indicated by the dotted lines 45, 46 and 47, permitting a knife or 60 other instrument 48 to penetrate at some point to lift out the weakened portion, which can be readily bent down again for sealing the contents.

As will be noted, the resistance of the composite closure structure permits the weight of the 65 contents, after the seal or diaphragm is broken, to force the closure open for dispensing but immediately closes when the carton is placed in its upright position. It is therefore, automatic in its 70 action, and should there be any tendency to stick, the closure is readily released by a finger.

The slots 23, 24, 29 and 30 are provided so that any convenient instrument such as a spoon 48, a nail or knife may be used to rupture the 75 diaphragm and lift the closure.

This arrangement of dispensing and closure means is economical from a manufacturing standpoint, since where the boundaries of the closure are merely weakened, only the cost of forming the weakened lines is reckoned, while 5 in such cases where the closures are formed by slitting, the additional cost includes only the cost of the diaphragm and its attachment. This container complete costs no more to manufacture than present containers cost to prepare them for 10 the spouts; therefore, the entire cost of the spouts is saved.

It will be understood that variations in construction and arrangement of parts which are consistent with the appended claims may be resorted to without detracting from the spirit or scope of the invention or sacrificing any of the advantages thereof.

I claim:

1. In a container, a body, a cover provided with a rim extended over a portion of the outer surface of said body, a closure consisting of a tongue lying between two outwardly converging slits formed in the main portion of the cover and continued into a portion of said rim, the rim ends of the slits being connected by a cross slit in the rim so arranged as to provide an angular sealing lip for said tongue, and a diaphragm of resilient flexible material adhering to the outer surface of the main portion of said cover and extended over 30 said rim in such manner as to normally urge the body portion of the tongue and its angular lip to closed position.

2. In a container, a body, a cover provided with a rim extended over and fixedly secured to a portion of the outer surface of said body, a closure consisting of a tongue lying between two outwardly converging slits formed in the main portion of the cover and connected at their outer ends by a cross slit, the main portion of said cover having an implement receiving slot located contiguously to said tongue, and a diaphragm of resilient flexible material adhering to said cover and said rim and extended over the tongue and the implement receiving slot in such 45 manner as to normally urge the tongue to closed position, said diaphragm being of sufficient area to seal the slot while the tongue is in closed position.

3. In a container, a body, a cover provided with a rim extended over and secured to an adjacent portion of the outer surface of said body, a closure consisting of a tongue lying between two outwardly converging slits formed in the main portion of the cover and continued at their outer ends into a portion of said rim, the rim ends of said slits being connected by a cross slit in the rim so arranged as to provide an angular sealing lip for said tongue, said body having a removable portion adhering to the underside of said sealing lip 60 and reinforcing the same.

4. In a container, a body, a cover provided with a rim extended over and secured to an adjacent portion of the outer surface of said body, a closure consisting of a tongue lying between two outwardly converging slits formed in the main portion of the cover and continued at their outer ends into a portion of said rim, the rim ends of said slits being connected by a cross slit in the rim so arranged as to provide an angular sealing lip for said tongue, the upper edge of said body having a removable portion adhering to the underside of the sealing lip and reinforcing said lip, and a diaphragm of flexible material adhering to said cover and extended over a portion of said 75

rim in such manner as to normally seal the tongue and its angular lip.

5. In a container, a body, a cover provided with a rim extended over a portion of the outer surface of said body, a closure consisting of a tongue lying between two outwardly converging slits formed in the main portion of the cover and continued into a portion of said rim, the rim ends of said slits being connected by a cross slit in the

10 rim so arranged as to provide an angular sealing

extremity for said tongue, said cover having an implement receiving slot located contiguously to said tongue, and a diaphragm of resilient flexible material adhering to said cover in such manner as to normally urge the tongue to closed position, 5 said diaphragm being of sufficient area to extend over and cover the slit portion of the rim and to seal said implement receiving slot, the tongue, and the angular extremity of the latter.

REED ELLIOTT JACOBS. 10
